Primary Examiner — Amy C Wierenga(74) *Attorney, Agent, or Firm* — Kinney & Lange, P. A.(57) **CLAIM**

The ornamental design for a clip with packings, as shown and described.

DESCRIPTION

FIG. 1 is a perspective view of a clip with packings;
 FIG. 2 is a front elevational view of a clip with packings;
 FIG. 3 is a rear elevational view of a clip with packings;
 FIG. 4 is a left side view of a clip with packings;
 FIG. 5 is a right side view of a clip with packings;
 FIG. 6 is a top plan view of a clip with packings; and,
 FIG. 7 is a bottom plan view of a clip with packings.
 The broken lines in the Figures are for environmental purposes only and form no part of the claimed design.

1 Claim, 4 Drawing Sheets(56)
